United States Patent Office.

JOHN E. CONE, OF CHICAGO, ILLINOIS.

Letters Patent No. 105,305, dated July 12, 1870.

GAS-HEATER.

The Schedule referred to in these Letters Patent and making part of the same

To all whom it may concern:

Be it known that I, JOHN E. CONE, of Chicago, in the county of Cook and State of Illinois, have invented certain new and useful Improvements in Heating Apparatus; and do hereby declare that the following is a full, clear, and exact description thereof, reference being had to the accompanying drawing, which is an elevation of the boiler, a portion being broken out to show the interior, and a plan view of the heater, showing the apparatus as applied to a portable house-lamp.

The object of this invention is to utilize the heat imparted in and by the ordinary process of illumination in houses, cars, &c., and cause it to convert water into steam, which, in turn, is conveyed into portable heaters, for warming the feet or for warming beds; and

The nature of the invention consists in the apparatus used to carry out this object.

In the drawing—

A represents a boîler, made of suitable sheet metal, of proper capacity, and steam-tight in all respects.

In the bottom of the boîler is a conical flue, B, reaching about one-half of its height, which flue is open at its bottom and closed at its top.

A cover, C, provided with suitable packing, fits tightly over an opening in the top of the boîler, and is secured in place by a bar, D, the ends of which pass through ears, E, on either opposite side of the top of the boîler, which ears are of such height to compel the bar to press closely upon the center of the cover.

A pipe-neck, F, of suitable metal, passes through said cover, and is attached to it rigidly.

The inner end of this pipe-neck reaches but a short distance below the cover into the interior of the boîler, and the other end passes outward over the boîler and downward, and has attached firmly to it a flexible pipe, G, suitably constructed, several feet in length, which, in turn, is firmly attached to one end of a coil of fixed metallic pipe, H, secured to the top of the heater I, the other end of said coil passing down into the interior of the heater.

This heater is a metallic or wooden box of small size, preferably about one foot square and three inches deep, water-tight, and provided with a spout or faucet, K. It may be upholstered in any ornamental or convenient manner.

The boîler A is also provided with a ring about its circumference, adjusted by a set-screw, M, for the purpose of suspending it by chains or rods attached thereto, and also for the purpose of attaching standards N, for use with a portable house-lamp upon a table.

The set-screw adjusts the position vertically of the ring, so that the boîler may be placed at the desired elevation above the flame used in connection with it.

In use, the boîler is to be half filled with water, with the cover fastened on tightly, and suspended or secured at a proper distance above any gas-jet or lamp, so as to receive the heat from its flame without obstructing its illuminating power.

The heat soon converts the water into steam, which, flowing out through the pipe F G into the coil H, heats said coil and the heater so that it may be used for the purposes before named.

Whatever portion of the steam enters the heater becomes condensed therein, and may at any time be poured out through the spout or faucet K.

Having thus fully set forth the nature and merits of my device,

What I claim as my invention, and desire to secure by Letters Patent, is—

The heating-apparatus above described, consisting of the boîler A, the pipes F, G, and H, and the heater I, when constructed, arranged, and operating substantially as and for the purpose set forth.

Witness my hand to these specifications and to duplicate drawing accompanying the same, this 23d day of March, A. D. 1869.

JOHN E. CONE.
